(57) **CLAIM**

The design for a lightning arrester, as shown.

DESCRIPTION

FIG. 1 is a perspective view of the lightening arrester according to the invention;

FIG. 2 is a left side elevational view of the lightening arrester according to the invention;

FIG. 3 is a right elevational view of the lightening arrester according to the invention;

FIG. 4 is a rear elevational view of the lightening arrester according to the invention;

FIG. 5 is a front elevational view of the lightening arrester according to the invention;

FIG. 6 is a top plan view of the lightening arrester according to the invention; and,

FIG. 7 is a bottom plan view of the lightening arrester according to the invention.

1 Claim, 7 Drawing Sheets

FIG. 1

FIG. 2

FIG. 3

FIG. 4

FIG. 5

FIG. 6

FIG. 7
